CONTROL DEVICE

Harold W. Rice, Los Angeles, Calif., assignor to
Robertshaw-Fulton Controls Company, a corporation of Delaware

Application August 7, 1947, Serial No. 767,269

6 Claims. (Cl. 137—66)

1

This invention relates to operating means for control devices and, more particularly, to combined safety and condition responsive operators for valves.

In my copending application, Serial No. 565,608, filed November 29, 1944, now U. S. Patent No. 2,504,049 issued April 11, 1950, there is disclosed a single valve having provision for operation through lever devices by both a thermoelectric safety device and an electric clock timer. The arrangement prevents operation of the valve by the clock unless the safety device permits. Thus, when the apparatus is installed on an appliance, such as a gas range, there can be no flow of fuel to the main burner unless the pilot burner is lighted and is causing the thermoelectric safety device to operate. Under these conditions the clock can automatically time a working operation by operating the valve between its controlling positions.

The foregoing arrangement is satisfactory as long as both forms of control are retained. In some cases, however, the clock control is not desired or it becomes necessary to remove it for repair or servicing. It is advantageous under these circumstances to insure operation of the appliance with safety even though the timing operation is dispensed with. Hence, an object of this invention is to operate a control device selectively by a combined safety and condition responsive means or by one of these means singly.

Another object of the invention is to simplify the changeover from the combined to single form of control by providing for an easy adjustment of the existing parts.

Another object of the invention is to afford easy access to the operating parts and particularly to those requiring manual operation in the functioning of the control.

Another object of the invention is to visually indicate the position of the operating parts during normal operation of the apparatus.

Other objects and advantages will become apparent from the following description taken in connection with the accompanying drawings, wherein:

Fig. 1 is a longitudinal sectional view in schematic form of a combined safety and condition responsive means having the invention applied thereto;

Fig. 2 is a front elevation of the structure shown in Fig. 1;

Fig. 3 is a rear elevation, partly in section, of the structure shown in Fig. 1;

Fig. 3a is a plan view of a detail;

2

Fig. 4 is a longitudinal section in schematic form of a combined safety and condition responsive operator showing a modified form of the invention;

Fig. 5 is a longitudinal sectional view similar to Fig. 4 but showing the parts in another operating position;

Fig. 6 is a rear elevation of the structure shown in Fig. 4; and

Fig. 7 is a side elevation, partly in section, of the structure shown in Fig. 4 but with the parts in still another operating position.

Referring more particularly to the drawings, Figs. 1 to 3 inclusive, the structure includes generally a control means 10, an actuating means 12 and a safety device 14 all of which will be described more fully hereinafter. The actuating means 12 is mounted upon the backguard 16 of a domestic gas range which has an aperture 18 formed in its front wall for the insertion of the control means 10 and the safety device 14 rearwardly thereof. A cover 20 is secured over the aperture 18 and serves to hide the control means 10 and safety device 14 from view. A support 22 which may take the form of a suitably bent plate is secured to the backguard 16 and serves to support the control means 10 and the safety device 14 in position.

The control means 10 comprises a generally rectangular hollow body 24 having an inlet opening 26 and an outlet opening 28 which are suitably threaded or otherwise formed for connection with fluid conduits or pipes 30 and 32 respectively. A partition 34 is formed integrally within the body 24 between the inlet opening 26 and the outlet opening 28 and is provided with a valve opening 36 providing communication therebetween. A valve member 38 is biased by a coil spring 40 against the partition 34 to control the flow of fluid through the opening 36. A valve stem 42 projects from the valve member 38 to the exterior of the body 24 and is reciprocable therein for positioning the valve member 38 against the bias of the spring 40.

The safety device 14 is of the electromagnetic type comprising a magnet housing 44 within which a horseshoe magnet 46 is rigidly mounted. An armature member 48 having a stem 49 is adapted to be moved into attracted position relative to the pole faces of the magnet 46 by means of a manually operable reset stem 50 which projects through the front cover 20. The movement of the reset stem 50 is transmitted to the armature 48 through a bell-crank 52 pivoted on the support 22 and attached to a U-shaped bracket

54 operable over the magnet housing 44 and through which the armature stem 49 projects. A coil spring 56 extends between the underside of the bracket 54 and the magnet housing 44. A detent 58 is provided on the armature stem 49 and overlies the bracket 54 so that the spring 56 is effective for biasing the armature 48 away from the pole faces of the magnet 46.

Any suitable means may be provided for energizing the magnet 46 of the safety device 14. In the copending application previously referred to thermoelectric means were provided for this purpose. Such means are indicated herein as comprising a winding 60 for the magnet 46 which is connected through conductors 62 and 64 to a suitable source of electrical energy such as a thermocouple (not shown). It will be understood that the energy provided by a thermocouple is insufficient to cause movement of the armature 48 to attracted position relative to the pole faces of the magnet 46 and that the manual resetting means previously described are relied upon for this operation. However, when the armature 48 has thus been reset, the energy so generated is sufficient to retain the armature 48 in attracted position against the bias of the coil spring 56.

The actuating means 12 takes the form of an electric clock having an actuating plunger 66 projecting therefrom for reciprocable movement between operating positions. The construction of the clock has no significance in this invention and any commercially available type of timing device would serve the purpose provided a reciprocating element such as the plunger 66 is associated therewith. In Fig. 1 of the drawings, the plunger 66 is shown in its retracted position which is maintained until the occurrence of the desired condition, such as the initiation of the timing period, when the plunger 66 moves to the left from the position shown. It will be understood that other condition responsive means could be substituted for the electric clock and that the conditions could be pressure, temperature, or humidity, among others.

The lever device of this invention takes the form, in the embodiments shown in Figs. 1 to 3 inclusive, of a pair of levers 68 and 70 respectively which, as will hereinafter appear, are adjustable bodily to a plurality of positions. In one of these positions the levers 68, 70 have operative relation with the control means 10, the actuating means 12 and the safety device 14. In the other one of these positions, the levers 68, 70 have operative relation with the control means 10 and the safety device 14 only. The arrangement is such that the lever device comprising levers 68, 70 will operate the control means 10 selectively by either the actuating means 12 and the safety device 14, or by the safety device 14 only.

The lever 68 comprises a substantially rectangular plate having one end projecting through an enlarged aperture 69 in the background 16 for overlying relationship at one free end with the actuating plunger 66. A suitable adjustment screw 72 projects from the lever 68 into operative engagement with the plunger 66. The opposite free end of the lever 68 is suitably bifurcated, as at 74, to straddle the valve stem 42 which it overlies. The support 22 is provided with an inwardly bent portion 73 projecting toward the lever 68 and having a rectangular slot 75 formed in the end face thereof. A bracket 76 is detachably secured by a screw 78 to the background 16 and is angularly formed, as at 80, to project through

the enlarged aperture 69 on one side of the lever 68. The lever 68 is provided with a pair of slots 81 and 82 for alternative use as will be apparent hereinafter. In the first position of the lever device as shown in the drawings, the angularly formed portion 80 of the bracket 76 extends through the slot 81 in the lever 68 and enters the slot 75 providing a tongue and groove connection with the support 22 as more clearly shown in Fig. 3a. The bifurcated end 74 of the lever 68 is provided with a pair of projections 83 which are formed on the side of the lever 68 adjacent the control means 10 and jointly provide an abutment for a purpose apparent hereinafter. Moreover, a portion of the support 22 which lies opposite the valve stem 42 is bent inwardly, as at 84, to provide an abutment for the lever 68 as will also be apparent hereinafter.

The lever 70 is also of substantially rectangular form but is flexible and somewhat wider than the lever 68. The lever 70 extends between the safety device 14 and the control means 10 by having a bearing at one end on the armature stem 49 and being provided with an enlarged aperture 86 through which the valve stem 42 freely projects. The upper wall of the aperture 86 is bent outwardly, as at 87, providing an inclined surface which will slide over the end of the valve stem 42 which may be suitably tapered to prevent binding at this point. A fulcrum for the lever 70 is provided by an inwardly bent portion 88 on the support 22 which has a reduced end projecting through an elongated aperture 90 in the lever 70 and defining a shoulder 89 on which the lever 70 may bear. Longitudinal movement of the lever 70 with the armature 48 is effected by a finger 92 on the bracket 54 which projects through a slotted portion on the lever 70 for pulling the same downwardly when the armature 48 is moved into attracted position with the pole faces of the magnet 46.

In order to indicate visually the position of the armature 48, the bracket 54 carries a laterally projecting arm 94 having a depending portion 96 in proximate relation with the rear face of the cover 20. The depending portion 96 carries the legends "On" and "Off" which may be viewed individually through a window 98 formed in the cover 20 for this purpose.

In the operation of the device it may be assumed that the parts are in the inoperative position shown in Figs. 1 to 3 inclusive of the drawings, that is, with the plunger 66 of the actuating means 12 in retracted position and the armature 48 disengaged from the pole faces of the magnet 46. Upon energy of sufficient value being supplied to the winding 60 of the magnet 46 by the thermocouple or other source, as described, the reset stem 50 is manually operated to place the armature 48 in its attracted position. Such operation will actuate the finger 92 to pull the lever 70 downwardly. The inclined surface 87 will slide over the valve stem 42 as the lever 70 undergoes a flexure and pivotal movement on the fulcrum 89 during its downward movement. Such operation will position the aperture 86 in the lever 70 below the valve stem 42. If the magnet 46 is sufficiently energized the lever 70 will be retained in the downward position so that the unperforated end portion of the lever 70 is interposed between the bifurcated end 74 of the lever 68 and the valve stem 42. The lever 70 is then in an operative position for transmitting movement to the valve stem 42 although such movement has so far not occurred.

At the appropriate time set by the clock forming the actuating means 12, the plunger 66 thereof will move to its extended position, that is, to the left as viewed in the drawing. The lever 68 will thereupon pivot in a counterclockwise direction on the fulcrum provided by the inwardly bent portion 73 of the support 22. This pivotal movement of the lever 68 is transmitted to the valve stem 42 through the interposed end of the lever 70 whereupon the valve member 38 is caused to move to open position against the bias of the coil spring 40. If the pipe 30 is connected to a source of fluid under pressure, then such fluid will be admitted to the outlet pipe 32 for delivery to the point of use.

At the expiration of the time period set by the clock, the plunger 66 is automatically retracted and the bias of the coil spring 40 causes the valve member 38 to move to the closed position. It is apparent that this movement of the valve member 38 toward closed position will cause the lever 68 to be rotated in a clockwise direction to the initial position shown in the drawings. It will be apparent, however, that the described control of the valve member 38 could be conducted through the agency of other condition controlling devices as previously indicated as well as by the clock of this embodiment.

If the energy supplied to the winding 60 ceases as by cooling of the thermocouple, then the armature 48 will no longer be retained in attracted position relative to the pole faces of the magnet 46. The coil spring 56 will operate under its bias to move the armature stem 49 upwardly and consequently return the lever 70 to its original position shown in the drawings. As the aperture 86 in the lever 70 is now located opposite the valve stem 42, the force exerted by the lever 68 cannot be transmitted to the valve stem 42 assuming that the plunger 66 is extended. Hence the valve member 38 is closed by the bias of the spring 40. The apparatus cannot be again placed in normal operation until the supply of energy to the winding 60 is restored as by heating of the thermocouple to which it is connected.

In the event that the actuating means 12 is not to be used or is removed for repair or other reasons, then the device nevertheless can be used with safety by a simple adjustment of the lever device to a second position. The screw 78 holding the bracket 76 is first removed to permit the bracket 76 to be detached from the backguard 16 carrying the lever 68 with this bracket 76. The lever 68 is then removed from the bracket 76 by sliding it off the end thereof. The bracket 76 and lever 68 are then reassembled with the angular portion 88 received within the slot 82 which serves as the alternative pivoting means for the lever 68. The bracket 76 carrying the lever 68 is then replaced on the backguard 16 with its end entering the slot 75 on the bent portion 73 of the support 22 and is secured with the screw 78. It will be apparent that the projecting end of the lever 68 no longer overlies the plunger 66 due to its lowered position. The projections 83 on the lever 68 are now positioned opposite the valve stem 42, while the projection 84 on the bracket 76 serves to limit clockwise rotation of the lever 68 in this position.

The operation of the device in the lowered position of the lever 68 is similar to that previously described. Thus, when the armature 48 is engaged with the pole faces of the magnet 46 and the lever 70 is pulled downwardly by the finger 92, then the projections 83 will serve as

spacers between the abutment 84 and the lever 70 to open the valve member 38 if the lever 70 is in its downward position. When the magnet 46 becomes deenergized, the lever 70 is moved upwardly until the aperture 86 is opposite the valve stem 42. The valve stem 42 is then free to move under the bias of the spring 40 for engaging the valve member 38 with the partition 34 and closing the opening 36 therein. The control means 10 is thus operated under control of the safety device 14 when the lever device is adjusted to its second position.

In the embodiment shown in Figs. 4 to 7 inclusive, similar reference numerals have been used to designate parts corresponding to those shown in Figs. 1 to 3 inclusive and further description of these corresponding parts is deemed unnecessary. In the modified arrangement the safety device 14 is positioned on the support 22 with the armature stem 49 substantially parallel with the valve stem 42. The reset stem 50 transmits motion directly to the armature 48 so that the intervening parts of the previous embodiment are dispensed with. In this modified arrangement a different form of lever device is also provided to accomplish the desired result of operating the control means 10 selectively either by the combined safety device 14 and actuating means 12 or by the safety device 14 alone.

The lever device of this alternative embodiment comprises a pair of levers 100 and 102 respectively and both being of channel-shaped form. The lever 100 is pivoted intermediate its ends on pin means 104 extending through the opposite sides thereof and carried by a channel-shaped bracket 106 which houses the levers 100, 102. In the first position, shown in Figs. 4, 5 and 6 of the drawings, the lever 100 extends in overlying relationship with the armature stem 49 and is free to pivot within the bracket 106 upon movement of the armature 48 to its released and attracted positions.

The bracket 106 is provided with a pair of substantially parallel slots 108 through which a pair of screws 110 extend for securing it in position on the support 22. The bracket 106 is longitudinally slidable relative to the support 22 upon loosening of the screws 110 and is guided during such movement by the provision of four spaced pins 112 of which there are two projecting from the support 22 into each of the slots 108 and located one on either side of the screws 110. The pins 112 also serve to limit the slidable movement of the bracket 106 by engagement with the opposite ends of the slots 108 as will be apparent. It will be understood that semi-positive stops could be utilized in place of the screw, pin and slot arrangement to ensure guided movement of the bracket 106 from one position to the other and its location in either upward or downward position.

The lever 102 is pivoted intermediate its ends on pin means 114 extending through opposite sides of the lever 100. The pivots 114 are preferably located on the lever 100 adjacent the free end thereof opposite that which overlies the armature stem 49. Thus, in the first lever position shown in Figs. 4, 5 and 6, the lever 102 has one free end overlying the plunger 66 and its opposite free end overlying the valve stem 42. A projection 116 is formed on the lever 102 intermediate the pivot 114 and the upper free end thereof for a purpose which will be apparent hereinafter.

In the operation of the device shown in Figs. 4 to 7 inclusive it may be assumed that the

plunger 66 has moved to the left as viewed in Figs. 4 and 5 and is therefore in its extended position for a timing operation by the clock forming the actuating means 12. The armature 48 is being retained in attracted position relative to the pole faces of the magnet 46 due to energy of sufficient value being supplied by the thermocouple or other source as described in connection with the previous embodiment. Consequently, in the position shown in Fig. 4 the bias of the coil spring 40 has been overcome and the valve member 38 is held in open position. This position of the parts is obtained by manual operation of the reset stem 50 serving to move the armature stem 49 to the left as viewed in the drawings, causing the lever 100 to rotate clockwise on the pivot 104. As the lever 100 carries the lever 102 it is apparent that such pivotal movement of the lever 100 causes the pivot 114 of the lever 102 to move clockwise also to the position shown in Fig. 4 of the drawing. Since the plunger 66 is in its extended position, a counterclockwise movement of the lever 102 then occurs about the pivot 114 which is sufficient to overcome the bias of the valve spring 40 and cause the valve member 38 to move to open position.

At the end of the timing period set by the clock, the plunger 66 will move to its retracted position, that is, to the right from the position shown in the drawings. The lever 102 will then be rotated in a clockwise direction on the pivot 114 by the valve stem 42 due to the valve member 38 being closed under the bias of the coil spring 40. During such operation of the clock the armature 48 is retained in its attracted position and no movement of the lever 100 occurs from the position shown in Fig. 4.

In the event that the energy supplied to the winding 60 of the magnet 46 is insufficient to retain the armature in the attracted position, then the parts assume the position shown in Fig. 5 of the drawings. Thus, the lever 100 can no longer retain the pivot 114 of the lever 102 in the position shown in Fig. 4 of the drawings and a counterclockwise movement of this pivot 114 occurs due to the bias of the valve spring 40. Such force is transmitted through the valve stem 42 to the lever 102 which pivots at its point of contact with the plunger 66 causing the described movement of the pivot 114 and consequent movement of the lever 100 to the position shown in Fig. 5 of the drawings. Thus, the armature 48 is forced away from the pole faces of the magnet 46 and the valve member 38 occupies the closed position shown in Fig. 5. As in the previous embodiment, the device cannot again be placed under control of the clock or actuating means 12 until the safety device 14 has been manually reset and the armature 48 is retained in an attracted position.

Upon loosening of the screws 110, the bracket 106 may be adjusted relative to the support 22 as previously described. The adjusted position is shown in Fig. 7 of the drawings, it being noted that the uppermost pins 112 have limited the downward movement of the bracket 106 by engagement with the upper ends of the slot 108. In this second position the levers 100 and 102 are adapted to occupy the same relative positions as shown in Figs. 4 and 5 of the drawings. Under the conditions described in connection with Figs. 4 and 5 the lever device operates similarly due to the provision of the projection 116 which acts as an abutment for the lever 102 in cooper-

ation with the support 22. Thus, the levers 100 and 102 occupy the full-line position shown in Fig. 7 of the drawings when the armature 48 is being retained in its attracted position and the valve member 38 is being held in open position. In the event that the armature moves to its released position as described in connection with Fig. 5, then the lever 102 will rotate about the projection 116 as a fulcrum instead of rotating about the plunger 66 as previously described. The levers 100 and 102 will then be moved to the broken line position shown in Fig. 7 of the drawings due to the bias of the valve spring 40, it being noted that such lever positions are equivalent to those shown in Fig. 5 of the drawings except that the overlying relationship with the plunger 66 has been dispensed with.

It will be understood that many changes may be made in the details of construction and arrangement of parts without departing from the scope of the invention so that this description and accompanying drawings are intended by way of illustration only and are not to be construed in a limiting sense.

I claim:

1. The combination comprising: control means; a support member; a lever member carried by said support member and adjustable bodily to a plurality of operative positions; a condition responsive safety device cooperable with said lever member and operable in all positions of said lever member to establish an operative relation between said lever member and said control means in the presence of said condition and to preclude said operative relation in the absence of said condition; actuating means for moving said lever member into operative engagement with said control means while said condition is present, said lever member being operatively associated with said actuating means in one of said positions and independent of said actuating means in another of said positions; and means on one of said members cooperable with the other said member in said other position for positioning said lever member in operative engagement with said control means while said condition is present.

2. The combination comprising: control means biased to a controlling position; a support member; a lever member carried by said support member and adjustable bodily to a plurality of operative positions; an electromagnetic safety device having an armature cooperable with said lever member and adapted to be retained in attracted position to maintain an operative relation between said control means and said lever member; actuating means for moving said lever member into operative engagement with said control means to overcome said bias while said armature is in attracted position, said lever member being operatively connected with said actuating means in one of said positions and being independent of said actuating means in another of said positions; and means on one of said members cooperable with the other said member in said other position for positioning said lever member in operative engagement with said control means to overcome said bias while said armature is in attracted position.

3. The combination comprising: control means biased to a controlling position; a support; a lever device carried by said support to be adjustable bodily to a plurality of operative positions and including a pair of pivoted levers; an electromagnetic safety device having an armature operatively connected with one of said levers and

adapted to be set and retained in attracted position to establish and maintain an operative relation between said control means and the other of said levers; actuating means cooperable with said other lever in a first position of said lever device for moving said other lever into operative engagement with said control means to overcome said bias while said armature is in attracted position, said lever device having a second position in which cooperation of said other lever with said actuating means is precluded; and abutment means on said other lever cooperable with said support in said second position for positioning said other lever in operative engagement with said control means to overcome said bias while said armature is in attracted position.

4. The combination comprising: control means biased to a controlling position; a support; a pair of pivoted levers carried by said support; an electromagnetic safety device having an armature operatively connected with one of said levers and adapted in attracted position to position said one lever in operative engagement with said control means; actuating means cooperable with the other of said levers in a first position thereof for pivotally moving said other lever into operative engagement with said one lever to position said one lever to overcome the bias of said control means while said armature is in attracted position, said other lever having a second position in which cooperation thereof with said actuating means is precluded; and abutment means on said support cooperable with said other lever in said second position for positioning said other lever in operative engagement with said one lever to position said one lever to overcome said bias while said armature is in attracted position.

5. The combination comprising: control means biased to a controlling position; a support; a pair of levers; an electromagnetic safety device having an armature operatively connected with one of said levers and adapted in attracted position to position said one lever in operative engagement with said control means; a detachable bracket carried by said support, the other of said levers being adapted for pivotal mounting in first and second positions on said bracket; actuating means cooperable with said other lever in said first position for pivotally moving said other lever into operative engagement with said

one lever to position said one lever to overcome the bias of said control means while said armature is in attracted position, said actuating means being independent of said other lever when said other lever is in said second position; abutment means carried by said other lever; and abutment means on said bracket cooperable with said other lever when said other lever is mounted in said second position to position said abutment means carried by said other lever in operative engagement with said one lever to position said one lever to overcome said bias while said armature is in attracted position.

6. The combination comprising: control means biased to a controlling position; a support; an adjustable bracket secured to said support; a first lever pivotally mounted on said bracket; a second lever pivotally mounted on said first lever; an electromagnetic safety device having an armature operatively connected with said first lever and adapted to position said first lever to maintain an operative relation between said second lever and said control means when said armature is in attracted position; actuating means cooperable with said second lever in a first position of said bracket for moving said second lever into operative engagement with said control means to overcome said bias while said armature is in attracted position, said bracket having a second position in which cooperation of said second lever with said actuating means is precluded; and abutment means on said second lever cooperable with said support when said bracket is in said second position for positioning said second lever in operative engagement with said control means to overcome said bias while said armature is in attracted position.
